UNITED STATES PATENT OFFICE.

ZEB ALLEN DYER AND HORACE H. DUBENDORF, OF LONG BEACH, CALIFORNIA, AS-SIGNORS TO FREDERICK W. HUBER, OF RIVERSIDE, CALIFORNIA.

CUP-PACKING GASKET FOR OIL-WELL-CEMENTING PLUGS.

Application filed May 17, 1924. Serial No. 714,128.

To all whom it may concern:

Be it known that we, ZEB ALLEN DYER and HORACE H. DUBENDORF, citizens of the United States, residing at Long Beach, California, have invented certain new and useful Improvements in Cup-Packings Gaskets for Oil-Well-Cementing Plugs, of which the following is a specification.

This invention relates to the art of drilling wells such as oil wells and the like and especially to the cementing of such wells.

More particularly the invention relates to a cup packing for oil well packers or plugs.

In the cementing of oil wells certain methods are used at times which require the employment of upper and lower packers to properly cause the very fluid cement or grout to flow up in the space between the tube used in the well as a casing and the wall of the well bore. Such a method may be typified by the utilization of apparatus as shown and described in the patent issued to Perkins and Double bearing the number 1,011,484 and it will be noted from this

25 patent that it is especially necessary to have the upper packer so constructed that no leakage of the water pumped in can take place downwardly past the packer. Heretofore it has been customary to employ a cup packing adjacent the upper end of the packer with a view to prevent such leakage but the cup packings employed have been found to be defective in function owing to the material from which they have been

35 made being insufficiently plastic and elastic in its nature and also owing to the cup not being shaped to cause it to adjust itself to the inequalities in the tube caused by corrugations, joints, rivets and so forth.

40 The principle and most important objects of the present invention are to overcome the defects of the cup packings previously used for this purpose by the provision of an improved cup packing made from a highly elastic material capable of fitting readily under fluid pressure from above into depressions and being also capable of fitting closely around projections, the cup furthermore being of novel form.

45 With the above and other objects in view, as will be hereinafter apparent, the invention consists in general of a cup packing of improved form constructed of highly elastic and plastic material, it being understood that the term plastic is used in the sense of

material conforming readily to inequalities under pressure but not necessarily retaining the impression of such inequalities when the pressure is removed.

The accompanying drawings illustrate the 60 form in which the packing is made and in these drawings like characters of reference indicate like parts in the several views, and:—

Figure 1 is a view partly in elevation and 65 partly in section showing a packer equipped with the improved cup packing being introduced into the upper end of an oil well casing or tube.

Figure 2 is a section through a corrugated 70 tube showing the manner in which the packing springs into a corrugation and the position of the packing before pressure is applied.

Figure 3 is a view similar to Figure 2 but 75 showing the effects of pressure on the packing under the conditions illustrated in that figure.

Figure 4 is a view similar to Figure 2 but showing the manner in which the packing 80 tends to conform to the recess at an ordinary screwed joint.

Figure 5 is a vertical section showing the manner in which the packing conforms to a rivet head projecting inwardly from the cas- 85 ing wall.

Figure 6 is a section on the line 6—6 of Figure 5.

Figure 7 is a cross section showing the manner in which the packing conforms to a 90 riveted pipe distorted in shape.

By reference to the accompanying drawings it will be seen that this packing is designed to be carried at the upper end of a packer or plug 10 and to be secured thereon by a follower plate 11. The packing itself consists of a flat circular body 12 having a centrally disposed opening for the screw of the follower plate 11. Around this body there projects upward a peripheral 95 flange the lower part 13 of which is perpendicular to the body and is of uniform thickness throughout. Above this uniformly thick portion the packing flares outwardly in a reversely curved portion which decreases in thickness from its junction with the portion 13 upwardly and carries on its upper edge a beading 15 so that a constricted portion or neck 16 lies just below the beading.

- This packing is formed of material which is of highly elastic nature so that it always returns to its shape after being deformed by pressure against the inequalities of the tube. Furthermore, the character of the material is such that it conforms, in use, closely to all such inequalities and thereby maintains a tight joint between the packer and the tube which prevents all leakage.
- 10 Preferable material for the purpose is found to be a pure rubber, this being a relatively cheap and readily available material having the required properties in the necessary degrees.
- 15 An inspection of the various examples illustrated will clearly show the manner in which a cup packing constructed in this manner and of this material conforms to inequalities of various types and further description of the action of the packing under the different conditions shown is not deemed necessary.
- 20 There has thus been provided for the purpose above mentioned, a novel and efficient cup packing which fully accomplishes the objects set forth.
- 25 It is to be understood that the packing is

molded to form and that minor changes may be made in that form without departing from the principles on which the invention 30 is based. It is not, therefore, desired to restrict the invention to the precise form shown and described, but it is desired to include all such as properly come within the scope claimed. 35

Having thus described the invention, what is claimed as new is:—

A cup packing consisting of a flat circular body portion having an upstanding peripheral flange, the lower portion of said flange 40 being arranged approximately perpendicularly to the body, the portion of the flange above the body portion flaring outwardly in a reverse curve and gradually decreasing in thickness from the lower portion upwardly, said flange terminating in a beading at its upper edge, the beading being of greater thickness than the material just below the beading. 45

In testimony whereof we affix our signatures. 50

ZEB ALLEN DYER.
HORACE H. DUBENDORF.
